LADY'S UNDERGARMENT

Marion C. Morin, Fairfield, Conn.

Application May 19, 1948, Serial No. 38,017

3 Claims. (Cl. 2—43)

1

This invention relates to ladies' girdles, corselets, and girdle-like undergarments.

A good many women discard their corselets and girdles in the summer when not wearing stockings, as under those conditions they have nothing to keep the garment down in proper place, or to prevent it from sliding up out of position. It is, therefore, an object of this invention to provide a garment of this type which will be held in position and cannot slide up out of place even when no stockings are being worn.

It is also an object to provide this type of garment which can be worn either with or without stockings, and the garment will be retained in proper place comfortably.

It is a further object to provide a garment of this type which gives greater freedom when the wearer is sitting down or bending over, and which does not slide up out of position or require to be pulled down after the wearer straightens up.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a front view showing one form of garment embodying this invention;

Fig. 2 is a back view thereof;

Fig. 3 is a front view showing it applied to a somewhat different type of garment;

Fig. 4 is a section of the garment substantially on line 4—4 of Fig. 3;

Fig. 5 is a back view of the garment of Fig. 3;

Fig. 6 is a front view of the garment showing a modification;

Figs. 7 and 8 are front and back views respectively showing another modification, and

Fig. 9 is a front view showing another modification.

Referring first to Figs. 1 and 2, this garment shows a girdle 10 in one piece which may be knitted or woven in a continuous piece without seams, or, as shown, has a seam 11 in one side, or if preferred there could be more than one piece with a seam at each side. At its lower end it is made somewhat longer than it would be normally and is provided with a pair of bands 12 in the form of continuous loops connected to the garment at the outer side but separated from it on the inner side, so as to pass snugly about the legs of the wearer and through or just below the crotch, so as to hold the garment

2

down in position and prevent it from sliding upwardly. These bands may be woven or knitted as one piece with the garment, or could be formed as separate pieces and fastened or stitched to the garment, as suggested in some of the other forms shown. The bands may be of somewhat elastic material, or woven of flexible fabric. The width may vary, as found desirable, but ordinarily it is desired it be not less than about an inch and one-half in width. It will be evident that with this construction, even when the garment is worn without stockings and garters suspended from the garment to support these stockings, the garment is held down in place by these bands, with no chance of its sliding up while being worn. However, if desired, garters can, of course, be suspended from the garment and stockings worn as with an ordinary garment.

In the form of Figs. 3, 4 and 5 a corselet type 20 of garment is shown, involving a lower portion 13 functioning as a girdle and an upper portion 14 functioning as a brassière. In the structure shown, the girdle portion comprises side panels 15 with intermediate front and back panels 16 and 17 between them and stitched to them, as indicated at 18, the front and back panels being extended above the panels 15 and shaped to provide the brassière 14. The lower ends of the side panels are extended downwardly somewhat further than would normally be the case, as indicated at 19, and connecting the free edges of the extended portions, both at the front and back, are flexible bands 20 extending at the inner sides of the legs 21 of the wearer through the crotch, the same as in the first form, these bands, together with the extensions 19 of the side panels forming the continuous loops to snugly embrace the legs of the wearer to keep the garment down in position, to prevent it from sliding upwardly, even if it is worn without garters or stockings. In the form shown in Figs. 3, 4 and 5, the bands 20 are shown as separate strips stitched to the extensions of the side panels 13, or if preferred they could be woven or cut integral with these panels, as indicated in Fig. 9, the panels being indicated at 13a and the bands at 20a. In Figs. 3, 4 and 5, garters 22 are shown as being applied to the garment, but it will be understood the garment may be worn either with or without garters and either with or without stockings.

In Fig. 6 the garment panel construction similar to that of Figs. 3, 4 and 5 is shown as a girdle only, the brassière being omitted. This 55 garment therefore comprises the two side panels 23 and an intermediate panel 24 at the front and a similar panel (not shown) at the back

located between and joining the free edges of the side panels and stitched to them by lines of stitching as shown at 25. In this construction, as in Figs. 3, 4 and 5, the side panels are extended as shown at 26, somewhat lower than normal, and below the lower edge 27 of the intermediate front and back panels, to which extensions are secured the bands 28 corresponding to the bands 12 of the other forms, these bands snugly fitting the legs of the wearer and extending through or just below the crotch to retain the garment in place and prevent its sliding upward, the bands and the side panels forming the continuous loops.

In the modification of Figs. 7 and 8, the construction may be the same as any of the forms shown, except that instead of extending the side panels indicated at 28, below the lower edges of the intermediate front or back panels 30 and 31, the lower edges of the panels are carried to substantially the same level, but the lower edges of the intermediate panels 30 and 31 are cut back or curved upwardly above the lower edges of the side panels, as indicated at 32, to give more freedom and clearance, and the bands 33 corresponding to the bands 12, 29 and 28, of the other forms, are secured to the lower end portions of the side panels as indicated by the lines of stitching 34, and form complete loops extending through the crotch or immediately below, snugly embracing and fitting the legs of the wearer to prevent the garment sliding up out of position.

It will be understood from the above that in this garment it is cut and fashioned as a complete garment and is worn as such, and the bands, or retaining means keep it in proper position. The securing or holding means is not an attachment put onto the garment structure, but is a part of the garment itself. It will also be clear from the description and drawing that this holding means can be applied to form a part of any of the various types of girdle or girdle-type garment, whether fashioned with or without such other types of garments, such, for example, as brassières. It will also be understood that all forms can be used with garters for supporting stockings, and these garters may be either permanently or detachably fastened to the garment, but that in either case, whether worn with or without stockings and garters, the garment will be comfortably held and retained in position and will be held against sliding upwardly out of place. It provides greater freedom with the wearer sitting down or bending over, and does not slide up in these positions so as to require that the garment be pulled down after the wearer straightens up.

It will be understood that in all forms the retaining bands may be cut or formed in one piece with the girdle portion of the garment, or they may be formed as separate elements and attached to the garment. In the case of stout persons these bands, by confining the upper part of the leg, materially reduce or eliminate the bulge in the leg where the ordinary garment ends, which is often noticeable due to this physical condition, thus producing or giving the desired continuous appearance or effect. In any case, the garment is held in proper position effectively, without any discomfort to the wearer.

Having thus set forth the nature of my invention, I claim:

1. A lady's girdle type undergarment comprising a girdle portion including opposite side por-

tions to snugly embrace and fit the hips of the wearer and intermediate portions extending between and joining the side portions for substantially the full length thereof to form the front and back portions of the garment, said side portions including lower end portions extending a short distance below the lower end edges of the intermediate portions, a pair of leg bands located immediately below the lower edges of the intermediate portions, each band extending between and attached at its ends to the front and rear inner upright edges of the lower end portion of one of the side portions which extends below the intermediate portions and being of substantially the same width as the amount the side portion extends below the intermediate portions, and said band forming with the side portion to which it is attached a complete loop to snugly embrace the leg of the wearer below and adjacent the crotch to hold the garment from sliding upwardly.

2. A lady's girdle type undergarment comprising a girdle portion including opposite side panels to snugly embrace and fit the hips of the wearer and intermediate front and back panels stitched at their upright edges to the edges of the side panels and extending between and connecting these panels, the lower end portions of the side panels being extended below the lower ends of the intermediate panels, and a pair of leg bands located immediately below the lower ends of the intermediate panels and each band extending between and connected at its ends to the front and rear edges of the lower end portion of a side panel which extends below the intermediate panels, said band being of substantially the same width as the extension to which it is connected and forming with this extension a continuous loop to snugly embrace and fit the leg of the wearer and extend through the crotch to retain the garment in proper position and prevent its sliding upward out of this position.

3. A lady's girdle-type undergarment comprising a girdle portion to snugly embrace and fit the hips of the wearer and including opposite side portions and intermediate portions extending between and connecting the side portions to form the front and back portions of the garment, the side portions arranged to fit the hips of the wearer and each side portion including a lower end portion extending a short distance below the lower ends of the intermediate portions, and a narrow leg band extending between and connected at its ends to the front and rear upright edges of each of said lower extensions of the side portions, and each band forming with the extension to which it is attached a complete loop to snugly embrace the leg of the wearer and extend through the crotch to hold the garment in place and prevent it from sliding upwardly out of position.
